UNITED STATES PATENT OFFICE

ANDREW GRAHAM SHIELDS, OF ATTLEBORO, MASSACHUSETTS

DESIGN FOR A TOILET-ACCESSORIES CONTAINER

Application filed May 28, 1930. Serial No. 35,821. Term of patent 3½ years.

To all whom it may concern:

Be it known that I, ANDREW GRAHAM SHIELDS, a citizen of the United States, residing at Attleboro, county of Bristol, and State of Massachusetts, have invented a new, original, and ornamental Design for Toilet-Accessories Container, of which the following is a specification, reference being had to the accompanying drawing, forming a part thereof.

I claim:

The ornamental design for a toilet accessories container as shown.

ANDREW GRAHAM SHIELDS.
